UNITED STATES PATENT OFFICE.

OWEN E. GRIGSBY, OF PARK RIDGE, ILLINOIS, ASSIGNOR TO GRIGSBY-GRUNOW-HINDS CO., OF CHICAGO, ILLINOIS, A CORPORATION OF ILLINOIS.

DESIGN FOR A COMBINED WEATHER SHIELD AND GLARE VISOR.

Application filed July 14, 1923. Serial No. 6,778. Term of patent 14 years.

To all whom it may concern:

Be it known that I, OWEN E. GRIGSBY, a citizen of the United States, residing at 419 No. Prospect Ave., Park Ridge, in the county of Cook and State of Illinois, have invented a new, original, and ornamental Design for Combined Weather Shield and Glare Visor, of which the following is a specification, reference being had to the accompanying drawing, forming part thereof.

Fig. 1 is a perspective view showing my new design; and

Fig. 2 is an enlarged end view of Fig. 1.

I claim:

The ornamental design for a combined weather shield and glare visor, as shown.

OWEN E. GRIGSBY.
